(57) CLAIM

The ornamental design for a clothing emblem, as shown and described.

DESCRIPTION

FIG. 1 is a front, bottom, left perspective view of a clothing emblem, showing my new design;

FIG. 2 is a front elevation view thereof;

FIG. 3 is a rear elevation view thereof;

FIG. 4 is a right elevation view thereof, the left elevation view being a mirror image thereof;

FIG. 5 is a top plan view thereof;

FIG. 6 is a bottom plan view thereof; and,

FIG. 7 is a front, right, perspective view thereof in a state of use.

The broken line showing of a sleeveless shirt is for the purpose of illustrating environment structure and forms no part of the claimed design. The broken line shown in the drawings illustrate portions of the clothing emblem that form no part of the claimed design.

1 Claim, 7 Drawing Sheets
